UNITED STATES PATENT OFFICE.

STEPHEN WOODS, OF UPPER MONTCLAIR, NEW JERSEY.

DESIGN FOR A BOX.

47,678.

Specification for Design.

Patented Aug. 3, 1915.

Application filed May 14, 1915. Serial No. 28,211. Term of patent 3½ years.

To all whom it may concern:

Be it known that I, STEPHEN Woods, a citizen of the United States of America, residing at Upper Montclair, in the county of Essex and State of New Jersey, have invented a new, original, and ornamental Design for Boxes, of which the following is a specification, reference being had to the accompanying drawing, forming part thereof.

The figure is a perspective view of a container showing my new design.

I claim—

The ornamental design for a box, as shown.

STEPHEN WOODS.
